Primary Examiner — Lilyana Bekic*(74) Attorney, Agent, or Firm* — Patterson Thuente Pedersen, P.A.(57) **CLAIM**

We claim the ornamental design for an oral airway device, as shown and described.

DESCRIPTION

FIG. 1 is a top perspective view of an oral airway device according to an embodiment.

FIG. 2 is a bottom perspective view of the oral airway device depicted in FIG. 1.

FIG. 3 is a right side elevational view of the oral airway device depicted in FIG. 1.

FIG. 4 is a left side elevational view of the oral airway device depicted in FIG. 1.

FIG. 5 is a top plan view of the oral airway device depicted in FIG. 1.

FIG. 6 is a bottom plan view of the oral airway device depicted in FIG. 1.

FIG. 7 is a front elevational view of the oral airway device depicted in FIG. 1; and,

FIG. 8 is a rear elevational view of the oral airway device depicted in FIG. 1.
